(57) **CLAIM**

The ornamental design for a cleat locking design, as shown and described.

DESCRIPTION

FIG. 1 is a top front view in perspective showing my new design;

FIG. 2 is a top rear view in perspective thereof;

FIG. 3 is a top view in plan thereof;

FIG. 4 is a front view in elevation thereof; and,

FIG. 5 is a rear view in elevation thereof.

The bottom of the cleat locking design does not form any part of the invention and is not shown.
